AIR PUMP

David Gregg, Caldwell, N. J., assignor to Eclipse Aviation Corporation, East Orange, N. J., a corporation of New Jersey

Application September 27, 1933, Serial No. 691,218

1 Claim. (Cl. 230—152)

This invention relates to fluid pumps and more particularly to vane pumps. In vane pumps as heretofore made, the housing is either of the cylindrical type with short spring-pressed vanes or of the non-circular conchoidal type with vanes extending diametrically of the housing, the shape of the housing being defined by the movement of the vane ends. Conchoidal housings and other non-circular forms are expensive to manufacture and spring-pressed vanes involve numerous small parts and introduce frictional losses.

The present invention contemplates the use of a cylindrical housing with diametrically extending vanes in which centrifugal force is used to cause the blades to follow the housing and the blades are substantially of the same length as the chordal dimension of the cylinder taken at right angles to a plane including both the center of the housing and the center of the rotor, that is, the blades are slightly shorter than the housing diameter.

An object of the invention is to provide a vane pump which may be cheaply manufactured without sacrificing operating efficiency.

Another object of the invention is to provide a pump with a cylindrical housing in which the ends of the blades abut at some portion of their movement in order to move one of the blades beyond the center of the rotor whereby centrifugal force will cause it to follow the cylinder contour.

Other features and objects of the invention will be apparent from the following description in connection with which a preferred embodiment of the invention has been illustrated in the accompanying drawing in which:

Fig. 1 is a longitudinal section through the pump;

Fig. 2 is a sectional top plan view taken along line 2—2 of Fig. 1;

Fig. 3 is a front elevation of the pump;

Fig. 4 is a section observed along line 4—4 of Fig. 1;

Fig. 5 is another section observed along line 5—5 of Fig. 1;

Fig. 6 is an isometric view of the vanes of the pump; and

Fig. 7 is a modified form of the invention.

Referring to the drawing, and particularly Figs. 1 to 6, the pump body generally designated at 3 comprises a portion 4 having a cylindrical liner 7 within which is an eccentric rotor 6 supported in the reduced portion 5 of the pump body by a bushing 9. The rotor is adapted to be driven

by shaft 13, the squared end 14 of which is pressed into a sleeve 17 secured to the reduced portion 18 of the rotor by a pin 19. A grease cup 20 is provided for lubrication of the parts, and studs 21 form a convenient means of attachment to the housing of an engine (not shown).

The rotor 6 is slotted at 22 and 23 for the reception of two pairs of vanes or blades 24 having cut-out portions 28 to permit the vanes to move relatively to each other in the diametrically arranged slots 22 and 23. The vanes 24 are identical and of a length such that the combined length of one pair is substantially equal to the chord of the liner 7 that is perpendicular to a plane including the axes of both the liner and the rotor.

The rotor may be driven in either direction but is shown as rotating in the direction of the arrow in Fig. 4. Recess 39 in cover 33 forms the pump outlet and recess 41 forms the pump inlet. The recesses communicate with pipes 37 and 38 respectively for connecting the pump to any instrument or device with which the pump is to be associated.

During pump operation, as shown in Fig. 6, the horizontal blades 24 have their inner ends 29 in contact while the vertical blades are separated because the upper vertical blade has been moved outwardly by centrifugal force to contact the liner 7, it being understood that each blade will follow the circular path shown in dotted lines.

To prevent wear on the liner and ends of the vanes, lubricant is introduced to the pump through a check valve 51 arranged on the compression side of the pump and which is connected by pipe 52 to any suitable source of lubricant supply.

In the form of the invention shown in Fig. 7 two vanes 42 and 43 are used which are identical, and to all intents and purposes the same as vanes 24 if their inner ends 29 were joined.

In the operation of the pump shown in Figs. 1 to 6, rotation in the direction of the arrows causes fluid to be drawn into the expansion chambers 25 through pipe 38 until the sides of the vanes 24 have passed the end of recess 41, after which it is forced from compression chambers 26 into pipe 37 until the vanes have passed beyond the end of elongated recess 39. The operation of the pump is well known, but it will be noted that the path described by the ends of the blades is circular, the center of the path is at 0, and the vane, remote from the point of tangency of the rotor and the liner 7, moves outwardly in its slot by centrifugal force. It will also be noted

that as each blade moves from its horizontal position toward the point of tangency that its inner end will contact the corresponding end of the blade in the same slot and force it outwardly from 5 the center of the rotor whereby each blade is positively started on its outward movement.

In the operation of the form of the pump shown in Fig. 7, as each blade approaches the point of tangency the center of the mass of each blade 10 will move outwardly from the center of the rotor, and centrifugal force will cause the blade to follow the liner. In this form of the invention the blade will not contact the housing at the point of tangency; therefore, the clearance between the rotor 15 and housing must be slight. Theoretically, some loss will occur at this point, but by introducing lubricant adjacent the point of tangency in the manner described, the loss of pressure is negligible by reason of the lubricant sealing effect.

20 While two forms of the invention have been shown and described, it is understood that this showing and description are illustrative only and that the invention is not regarded as limited to the forms shown and described or otherwise, except 25 by the terms of the following claim:

What is claimed is:

A fluid pump comprising a body having a cylindrical housing and plane surface end walls, a radially slotted rotor in said housing mounted eccentric to the housing, said rotor having a reduced extension rotatably supported in an opening in the body end wall, the other of said end walls being removable and having inlet and exhaust ports therein, a pair of straight sided flat blades slidably mounted in each slot of the rotor, each pair of said blades having an overall length substantially equal to a chord of the housing taken at right angles to a plane including the centers of both the housing and rotor, said blades being substantially identical and having cut-out central portions for permitting relative blade movement, said blades being arranged to have the sides thereof control the ports in the removable end wall, a cylindrical member drivably secured to said extension having a polygonal opening therein, said member and said extension forming a complete closure for the opening in the body end wall, and a polygonal drive shaft fitted in the opening of the member.

DAVID GREGG.
